ABSTRACT OF THE DISCLOSURE

Unsymmetrical oligoquaternary ammonium compounds containing at least two onium nitrogen atoms. Typical compounds are:

and

These compounds are effective as antimicrobial agents and as anticaries or anticalculus agents.

This application is a continuation-in-part of Ser. No. 716,412, filed Mar. 27, 1968, now abandoned and a continuation-in-part of Ser. No. 82,594, filed Oct. 21, 1970, now abandoned.

The present invention relates to unsymmetrical oligoquaternary ammonium compounds and, more particularly, to unsymmetrical oligoquaternary ammonium compounds containing at least two onium nitrogen atoms, having anti-microbial activity, having anti-caries properties and having novel adsorption and desorption properties.

In recent years a multitude of quaternary ammonium compounds having antifungal and antibacterial capabilities have been disclosed. These quaternary ammonium compounds may be divided into two major groups (A) those quaternaries having only one onium nitrogen atom and (B) those quaternaries having more than one onium nitrogen atom. The latter group can be subdivided into bisquaternaries having two onium nitrogen atoms and tri and higher quaternaries having three or more onium nitrogen atoms. Each of these subdivisions of the poly-onium nitrogen atom quaternaries can be further divided into the symmetrical and the unsymmetrical poly-onium nitrogen atom quaternaries dependent upon the substituent groups attached to the terminal onium nitrogen atoms of the poly-onium nitrogen atom quaternaries. Thus, when all of the substituent groups attached to each terminal onium nitrogen atom are the same, the quaternary is considered to be symmetrical. When one or more of the substituent groups attached to one terminal onium nitrogen atom of a poly-onium nitrogen atom quaternary is or are different from the constituent groups attached to the other terminal onium nitrogen atom the quaternary is considered to be unsymmetrical or asymmetrical.

Those skilled in the art will recognize that prior art descriptions of poly-onium compounds do not indicate that the efficacy is dependent upon the number of CH_2 -groups which separate the two onium-nitrogen atoms in the bis-quaternaries or that in the poly-onium compounds having three onium-nitrogen atoms that the efficacy is dependent upon the number of CH_2 -groups separating from the central onium-nitrogen atom the terminal onium-nitrogen atom to which is bonded an alkyl group hav-

ing ten or more carbon atoms. It has now been discovered that the number of CH_2 -groups separating the afore-said onium-nitrogen atoms is indicative of the efficacy of the germicidal properties and other properties such as cariostatic properties of the quaternary compound. In addition, the substantivity of these unsymmetrical quaternaries decreases as the concentration of methanol decreases in aqueous acid containing methanol in proportions varying from zero to fifty-five percent as will be discussed below with regard to chromatography tests.

The novel poly-onium nitrogen compounds of the present invention can be represented by the formula

wherein R is a substantially straight chain alkyl group having ten to eighteen carbon atoms; Y is selected from the group consisting of

25 n is an integer 2 to 18; R¹, R², R³ and R⁴ are lower alkyls having 1 to 3 carbon atoms; b is an integer 2 to 12; X is selected from the group consisting of chlorine, bromine and iodine; m is 0 to 3; p is 0 to 3; m+p is 0 to 3; An is a compatible anion, including halide, such as Cl, Br, or alkyl or phenyl sulfonate, such as CH_3SO_3^- , $\text{C}_2\text{H}_5\text{SO}_3^-$, $p\text{-CH}_3\text{C}_6\text{H}_4\text{SO}_3^-$, etc. in sufficient number to satisfy the positive valence of the remainder of the compound, that is, 2 or 3. The An groups may be the same or different.

30 Illustrative of the effect of the value of n in the formula set forth hereinbefore are the following data obtained in anti-microbial tests employing the following organisms:

Organism No.:

- 40 1 *Staphylococcus aureus* (gram positive bacteria)
- 2 *Corynebacterium acnes* (gram positive bacteria)
- 3 *Bacillus subtilis* (gram positive bacteria)
- 4 *Escherichia coli* (gram negative bacteria)
- 5 *Pseudomonas aeruginosa* (gram negative bacteria)
- 6 *Candida albicans* (fungus)
- 7 *Trichophyton mentagrophytes* (fungus)
- 8 *Aspergillus niger* (fungus)
- 9 *Streptococcus mitis* (S-3) (gram positive bacteria)

45 50 The serial dilution test to determine the minimal inhibitory concentration in $\mu\text{g./ml.}$, i.e., 1×10^{-3} mg./ml., has been used to illustrate this important characteristic of these novel poly-onium quaternary ammonium type materials. Two materials of this type, A and B, were used 55 and the chain length (n) varied from 3 to 10 (CH_2) groups.

60 65 70 In the above compounds, A and B as well as in structural formulae set forth hereinafter, Me indicates a methyl group.

n	Organism number							
	1	2	3	4	5	6	7	8
	μg./ml.	μg./ml.	μg./ml.	μg./ml.	μg./ml.	μg./ml.	μg./ml.	μg./ml.
Compound A								
3-----	25	2.5	25	>100	>100	12.5	125	1,000
4-----	50	>100	12.5	100	>100	25	>1,000	500
6-----	12.5	0.78	6.25	25	250	1.56	<7.8	250
8-----	1.56	<0.2	6.25	3.12	1,000	1.56	<7.8	31.2
10-----	0.78	0.025	1.56	12.5	>100	0.78	7.8	31.3
Compound B								
4-----	50	3.13	3.13	100	>100	25	125	1,000
10-----	1.56	0.78	0.78	6.25	15.6	0.78	<7.8	125

Compounds having values of *n*, ranging from low to 15 high, are effective antimicrobial agents. Generally, the compounds of greater effectiveness have higher values of *n*. Similar results may be observed when the methyl groups are replaced with ethyl and/or propyl groups.

The effect of a single nuclear substituent, such as a 20 halogen substituent in the benzyl ring is clearly shown by the following comparative results using the serial dilution test and reporting the minimal inhibitory concentration in $\mu\text{g./ml.}$, that is, 1×10^{-4} mg./ml. on compounds in which the chain length (*n*) was 4:

COMPOUND A v. COMPOUND A_{hal}

	Organism number							
	1	2	3	4	5	6	7	8
	μg./ml.	μg./ml.	μg./ml.	μg./ml.	μg./ml.	μg./ml.	μg./ml.	μg./ml.
A-----	50	>100	12.5	100	>100	25	>1,000	500
A _{hal} -----	6.25	0.78	6.25	25	100	12.5	31.3	125

COMPOUND B v. COMPOUND B_{hal}

	Organism number							
	1	2	3	4	5	6	7	8
	μg./ml.	μg./ml.	μg./ml.	μg./ml.	μg./ml.	μg./ml.	μg./ml.	μg./ml.
B-----	50	3.13	3.13	100	>100	25	125	1,00
B _{hal} -----	12.5	6.25	0.78	25	100	25	15.6	25

Generally speaking the presence of a nuclear substituent such as a halogen substituent in the benzyl ring 50 increases the antimicrobial effectiveness of compounds of the invention. In addition to or in place of the halogen substituent, alkyl substituent, such as methyl, ethyl or propyl, may be present in the benzyl ring.

The following compounds were also tested against the 55 organisms described above and the inhibitory concentration indicated results below were obtained:

COMPOUND C_{hal}

COMPOUND D_{hal}

	Organism number								
	1	2	3	4	5	6	7	8	9
	μg./ml.	μg./ml.	μg./ml.	μg./ml.	μg./ml.	μg./ml.	μg./ml.	μg./ml.	μg./ml.
C _{hal} -----	0.78	3.12	0.39	1.56	62.5	0.78	31.2	250	3.12
D _{hal} -----	0.39	3.12	0.19	0.78	31.2	0.78	1.9	62.5	0.39

Similar results may be obtained when the dodecyl and 75 tetradecyl groups of Compounds C_{hal} and D_{hal} are replaced by shorter substantially straight chain alkyl groups such as n-decyl or n-undecyl, an intermediate alkyl group

such as n-tridecyl and longer alkyl groups such as n-pentadecyl, n-hexadecyl, n-heptadecyl and n-octadecyl.

In addition to the antimicrobial effectiveness of compounds of the invention, compounds of the invention are also effective in reducing formation of caries in mammals as demonstrated below:

Caries-susceptible hamsters bred either from the Keyes strain or the NIDR (National Institute for Dental Research) strain in groups of 15 males and 15 females per 25 control group and per each test group were fed ad lib a

Mitchell cariogenic diet and received constant deionized water. Each day each hamster's teeth were swabbed 30 seconds by cotton tipped swabs, the control group with water and each test group with its test solution. After 6 weeks of swabbing the animals were sacrificed, and the defleshed heads were scored by a modified version of the Keyes scoring method. Mean averages and percentage

changes from the control group were determined and tested statistically to determine the significance.

The compounds were administered in 1% by weight 75 solutions.

RESULTS.—HAMSTER CARIES TEST

Compound	Caries reduction, percent	
	Males	Females
[n-C ₁₂ H ₂₅ N ⁺ (CH ₃) ₂ (CH ₂) ₁₀ N ⁺ (CH ₃) ₂ CH ₂ C ₆ H ₄ p-Cl]Br ₂	-75.4	-77.9
[n-C ₁₄ H ₂₉ N ⁺ (CH ₃) ₂ (CH ₂) ₁₀ N ⁺ (CH ₃) ₂ CH ₂ C ₆ H ₄ p-Cl]Br ₂	-51.7	-61.2

The results above indicate the significant effectiveness of the compounds of the invention in reducing caries formation.

When used against bacteria and fungi, compounds of the instant invention may be applied directly to the surface to be protected or may be used in a pharmaceutical carrier. Typically an effective amount, e.g. 0.1 to about 10% by weight of the quaternary is included in an inert liquid carrier such as water and a dispersing or surface active agent. Alternatively, an effective amount, e.g. 0.1 to about 10% by weight may be incorporated into a solid carrier which may be inert, such as talc, clay, diatomaceous earth, flour, etc.

When compounds of the invention are used in compositions which reduce formation of caries and of calculus, they are typically incorporated in oral preparations in non-toxic effective amounts which are compatible with the preparation (e.g. dispersible or soluble therein). Such amounts may be up to about 5% by weight of the oral preparation, generally about 0.1% or 0.15% to about 5%, preferably about 0.1% or 0.15% to about 2%, more preferably about 0.15% to about 1% and most preferably about 0.25% to about 0.5%. Typically the oral preparation is a dentifrice such as a dental cream, tablet or powder, containing as a vehicle about 20-95% by weight of a dentally acceptable water-insoluble polishing material preferably including water-insoluble phosphates such as di-calcium phosphate, tricalcium phosphate, insoluble sodium metaphosphate and calcium pyrophosphate. The dentifrice may also include water, binders such as glycerine, sorbitol, propylene glycol and polyethylene glycol 400, gelling agents such as Irish moss and sodium carboxymethyl cellulose, additional antibacterial agents, coloring or whitening agents, preservatives, silicones, chlorophyll compounds, additional ammoniated materials, flavoring or sweetening materials and dentally beneficial compounds which provide fluorine-containing ion such as sodium fluoride, stannous fluoride and sodium monofluorophosphate.

The oral preparation may also be a liquid such as a mouth rinse which typically contains 20-99% by weight of an aqueous alcohol vehicle, the alcohol being a cosmetically acceptable and nontoxic alcohol such as ethanol or isopropyl alcohol and being present in amount of about 5-30% by weight of the oral preparation.

Such oral preparations are typically applied by brushing the teeth or rinsing the oral cavity for 30-90 seconds at least once daily. Typical oral preparations including a compound of the instant invention are set forth as follows:

Component:	Dental cream	Parts by weight
Quaternary D _{hal}	0.5	
Sodium benzoate	0.15	
Saccharine	0.2	
Insoluble sodium metaphosphate	42.1	
Dicalcium phosphate dihydrate	5.0	
Titanium dioxide	0.4	
Gum tragacanth	1.4	
Oil of wintergreen	1.0	
Color	0.03	
Water	22.12	
Glycerine (99.3%)	27.10	

	Mouth wash	Parts by weight
15 Component:		
Quaternary C _{hal}	0.25	
Ethyl alcohol	14.782	
Flavor	0.318	
Glycerine	10.000	
Deionized water	74.1	
20 Color (1% solution)	74.1	

The relative substantivity of the novel poly-onium quaternary ammonium compounds of the present invention compared to mono-onium quaternaries and symmetrical bis and tetrakis quaternaries was studied on two substrates, viz. cellulose and polyamide by a chromatographic technique. R_{F'} and R_F values were determined in aqueous acid containing proportions of methanol varying from 0 to 55 percent. Compared to the other classes 25 of quaternaries the poly-onium quaternary ammonium compounds of the present invention show a decrease in substantivity as the concentration of methanol in the solvent decreases. These substantivity tests were carried out as follows:

35 Paper chromatography.—Whatman No. 1 paper was spotted with 2 μ l. aliquots of 1% solutions of the quaternaries. After overnight equilibration in a tank containing the solvent to be used, the chromatograms were developed in the descending manner to a distance of about 14 inches 40 at room temperature. After drying, the papers were dipped in a dilute ammoniacal solution of bromophenol blue and then held under running water until all removable dye had been washed away. The presence of quaternary is revealed by a bright blue spot (soluble in organic 45 solvents, but insoluble in water) against a white background; the color tends to fade with time, but can usually be restored by retreatment with bromophenol blue. Acid was necessary in the developing solvent to diminish streaking, but the relative positions of various quaternaries was 50 not different whether the solvent was neutral, acidic, or basic. The R_{F'} values were found to vary somewhat with the amount of quaternary applied to the paper; hence the solutions were carefully prepared to the same concentration, and the spotting was done with micro pipettes 55 to insure that equal quantities of all quaternaries were being compared. In addition, replicates were run on different days and the results averaged to obtain the values given in Tables I and II below.

60 Polyamide thin layer chromatography.—8 x 8 inch glass plates were coated in Kensco variable thickness applicator with approximately 250 micron layers of a slurry of Polyamide Woelm for TLC in chloroform-methanol. Uniform adherent layers were obtained on drying in a moderately humid atmosphere. These plates were spotted 65 with 8-10 μ l. aliquots of 1% solutions of quaternaries and developed in the ascending manner. After drying, visualization was accomplished by spraying with a fine mist of a 0.1% solution of Direct Fast Rubine WS dye (Ciba), whereupon the quaternaries were seen as pink 70 spots on a red background. Streaking was not a problem on these plates even when no acid was used in the solvent, but in the results reported in Table III, below, an acidic system was used.

75 Although these substrates are different in that one is a carbohydrate and the other an amide, the results were

found to correlate very closely as shown in FIG. 1 where for each quaternary the R_F' value obtained on paper is plotted against its R_F value on polyamide. The tendency of the points to fall on a straight line is evidence that the binding to paper is similar in nature to the binding to polyamide, and hence one can feel confident about extrapolating the results to protein and the specific types of surfaces present in the body. Most of the work was done on paper because of the greater convenience and the more sensitive detection system. Thus, the mono-quaternaries, $RNMe_2(CH_2)_xBr$, where R is n-dodecyl and x is 2,3, 4, 8 and 10 are represented by open circles; the symmetrical bisquaternaries, $RNMe_2(CH)_xNMe_2R$ where R is n-dodecyl and x is 6, 8 and 10, are represented by open squares; the unsymmetrical bisquaternaries and tris-quaternaries are represented by solid triangles, and the control, $RNMe_2CH_2\phi$, wherein R is n-dodecyl, by a solid circle.

Large differences in mobility were observed among the quaternaries as seen in the tabulation of results in the various solvents. It is particularly interesting to plot the results in the form of relative mobilities; relative, that is, to one quaternary chosen as a standard, namely n-dodecyldimethylbenzylammonium chloride. The ratio of the R_F value of any specific quaternary to the R_F value of the standard quaternary under the same conditions will be referred to hereafter as R_Q , and the ratio of R_F' values as R_Q' , where R_F and R_F' have the meanings ascribed to them in the literature. It was convenient to use R_F and R_Q for the polyamide chromatograms because the

quaternaries traveled in small regularly shaped spots, whereas R_F' and R_Q' were more appropriate values to measure on paper where the spots tended to be elongated and to have no easily located center of maximum density.

The bromoalkyl quaternaries show a large variation with molecular weight in R_Q' values plotted against methanol concentration in the developing solvent (FIG. 2). However, the series of symmetrical bisquaternaries and unsymmetrical bisquaternaries (FIG. 3) show little variation with molecular weight within each group, but display a striking difference between the two types. Although fewer examples of the unsymmetrical trisquaternaries are available they display the same behavior as the unsymmetrical bisquaternaries. The two quaternaries containing the p-chlorobenzyl group showed slightly greater binding than their analogs.

These data are from paper chromatography; although only two different solvent compositions were used for chromatography on polyamide, the slopes of the lines connecting these two points have the same direction as the curves obtained with paper, which is further evidence for the similarity of the binding for the two media.

$$R_F = \frac{\text{Movement of spot}}{\text{Movement of advancing front of liquid}}$$

$$R_F' = \frac{\text{Movement of leading edge of spot}}{\text{Movement of advancing front of liquid}}$$

In all cases in Tables I, II, and III, R represents
30 n-dodecyl.

From the comparative data showing the relative substantivity of the novel poly-onium quaternaries of the present invention and prior art mono-onium, and symmetrical bisquaternaries of the prior art those skilled in the art will recognize that the enhanced desorbability of these compounds makes them more readily available for disinfecting purposes than the less readily desorbed prior art quaternaries.

Those skilled in the art will also observe that in the unsymmetrical compounds of the present invention the increased spacing between the terminal onium-nitrogen

to which the oilophilic alkyl group is attached and the next onium-nitrogen increases the anti-microbial activity of these compounds whereas in the symmetrical bisquaternaries listed in Tables I-III, the activity is essentially unchanged.

70 The novel poly-onium quaternary ammonium compounds of the present invention can be prepared by the methods of organic chemistry known by those skilled in the art. Presently, it is preferred to obtain these novel poly-onium compounds by first preparing a quaternary ammonium compound by the reaction of a tertiary amine

13

poly-onium quaternary ammonium bromides thus prepared have the following characteristics:

	Cal.	Obs.
Bromine, percent.....	33.04	33.05
Melting point, °C.....	151-155	.....
Nitrogen, percent.....	5.79	5.86

	Cal.	Obs.
Bromine, percent.....	29.94	28.63
Nitrogen, percent.....	5.25	4.93

	Cal.	Obs.
Total halogen, percent.....	27.65	28.38

Although this invention has been described with reference to specific examples, it will be apparent to one skilled in the art that various modifications may be made thereto which fall within its scope.

What is claimed is:

1. An oral preparation comprising a dentally acceptable water-insoluble polishing agent and an effective compatible non-toxic amount of antimicrobial composition comprising about 0.1-5% by weight of an unsymmetrical poly-onium quaternary ammonium compound having the structural formula:

wherein

R is a substantially straight chain alkyl group having 10 to 18 carbon atoms,

Y is selected from the group consisting of

and

n is an integer 2 to 18;

R¹, R², R³ and R⁴ are lower alkyls having 1 to 3 carbon atoms;

b is an integer 2 to 12;

X is selected from the group consisting of chlorine, bromine and iodine;

m is 0 to 3;

p is 0 to 3;

m+p is 0 to 3; and

An is a compatible anion.

2. The oral preparation claimed in claim 1 wherein said unsymmetrical poly-onium quaternary ammonium compound is present in amount of about 0.1% to about 2% by weight.

14

3. The oral preparation as in claim 1 wherein said compound is

5 wherein Me is methyl.

4. The oral preparation claimed in claim 1 wherein said compound is

wherein Me is methyl.

10 5. An oral preparation comprising a cosmetically acceptable non-toxic alcohol and an effective, compatible non-toxic amount of antimicrobial composition comprising about 0.1-5% by weight of an unsymmetrical poly-onium quaternary ammonium compound having the structural formula:

20 wherein

R is a substantially straight chain alkyl group having 10 to 18 carbon atoms,

Y is selected from the group consisting of

25 and

R⁴ is an integer 2 to 18;

30 R¹, R², R³ and R⁴ are lower alkyls having 1 to 3 carbon atoms;

b is an integer 2 to 12;

X is selected from the group consisting of chlorine, bromine and iodine;

35 m is 0 to 3;

p is 0 to 3;

m+p is 0 to 3; and

An is a compatible anion.

40 6. The oral preparation claimed in claim 5 wherein said unsymmetrical poly-onium quaternary ammonium compound is present in amount of about 0.1% to about 2% by weight.

7. The oral preparation claimed in claim 5 wherein said compound is

45 wherein Me is methyl.

UNITED STATES PATENT OFFICE
CERTIFICATE OF CORRECTION

Patent No. 3,749,767 Dated July 31, 1973

Inventor(s) Robert Andrew Bauman

It is certified that error appears in the above-identified patent and that said Letters Patent are hereby corrected as shown below:

Cancel Column 6, line 22 to Column 10, line 69

Signed and sealed this 25th day of December 1973.
